SUPPORT FOR GEOMETRICAL
INSTRUMENTS

Otto F. Buzhardt, Greenville, S. C.

Application April 10, 1934, Serial No. 719,939

5 Claims. (Cl. 248—2)

My invention relates to improvements in geometrical instruments.

An important object of the invention is to provide a device of the above mentioned character, so constructed that angular positions for a hand level, with relation to a given line, may be readily obtainable.

A further object of the invention is to provide a device of the above mentioned character which 10 may be employed to obtain right angle positions, at a constant height of the instrument.

A further object of the invention is to provide means whereby the device may also be employed as a ranging implement.

15 Other objects and advantages of the invention will be apparent during the course of the following description.

In the accompanying drawing, forming a part of this specification, and in which like numerals 20 are employed to designate like parts throughout the same,

Figure 1 is a perspective view of a device embodying my invention,

Figure 2 is a central vertical longitudinal section through the device, and,

Figure 3 is a perspective view, separate, of the relatively rotatable elements included in the device.

In the drawing, wherein for the purpose of illustration is shown a preferred embodiment of my invention, the numeral 5 designates an up-standing or vertical rod or supporting member, preferably of wood. This rod is preferably cylindrical throughout the major portion of its length, 30 and is provided at its lower end with flat faces 6, as shown.

The numeral 7 designates an anchor element or foot, preferably in the form of an elongated flat metal plate. Rigidly attached to the top surface 40 of this foot or plate, near its center, are straps 8, preferably formed of metal and disposed at a right angle to the same. These straps have elongated slots 9, receiving bolts 10, passing through the lower end of the rod 5, at the flat 45 face 6. These bolts carry winged nuts 11, as shown. It is thus seen that the rod 5 may be vertically adjusted with relation to the straps 8 and clamped thereto in the selected adjusted position.

50 The foot or plate 7 has depending prongs 12, rigidly secured thereto, at the central longitudinal axis of the plate. These prongs are spaced and are preferably disposed outwardly of the straps 8. These prongs are to be forced into the ground or other support, within the previously as-

certained line. The foot or plate 7 is provided centrally thereof with an opening 13, arranged between the straps 8, for removably receiving a prong, to be described.

The numerals 14 and 15 designate companion clamp members, having depending flanges 16, to fit within notches 17 formed in the side edges of the foot or plate 7. These clamp members also have up-standing flanges 17 and 18, respectively. The up-standing flange 18 carries a winged bolt 19, having a swiveled connection therewith. This bolt also has screw-threaded engagement at 20 with the up-standing flange 17. By proper manipulation of the bolt 19 the clamp including the clamp members may be locked to the foot or plate 7, or removed therefrom. The clamp member 14 has a depending prong 21, rigidly secured thereto, and adapted to pass through the opening 13. The prong 21 is longer than the prong 12, and is adapted to be forced into the ground or other support, when the rod 5 is to be turned upon its longitudinal axis, for ranging purposes. When the device is not used for ranging purposes the clamp and prong 21 are removed from the plate or foot 7.

The upper end of the rod 5 is preferably slightly reduced in diameter, to receive thereon a sleeve 22, which may be held against turning movement upon the rod by frictional engagement, or by any other suitable means. A preferably circular plate or disk 23 is rigidly attached to the upper end of the sleeve 22, and is arranged in concentric relation thereto and extends radially beyond the sleeve for a substantial distance, as shown. A companion preferably circular plate or disk 24 is mounted upon the plate or disk 23, in concentric relation thereto, and is rotatable with relation to the same. The lower plate or disk 23 has depressions or recesses 25 formed in its upper surface and these depressions are preferably spaced 90° apart. The upper plate or disk 24 has a corresponding number of projections or lugs 25', also spaced 90° apart, and adapted to enter the recesses or depressions 25.

Arranged upon the upper surface of the upper disk 24 is a hand level holding element, which is U-shaped in cross section. The hand level is inserted within this holding element, and is clamped therein by adjustable bolts 26', as shown. The holding element 26 extends diametrically of upper disk, and one pair of the lugs 25 is disposed at the central longitudinal axis of the holding element. A vertical depending pin 27 is rigidly connected at its upper end with the disk 24 and holding element 26 and serves to rigidly

connect these parts, so that the elements 24, 26, and 27, move as a unit. The pin is slidably mounted in an opening 28, disposed centrally of the plate or disk 23. The pin 27 projects below the plate or disk 25 and is arranged within a longitudinal opening or chamber 29, formed in the upper end of the rod 5. A compressible coil spring 30 surrounds the pin 27 and engages the stationary plate or disk 23 and a cotter pin 31 adapted for insertion in selected openings 32, formed in the pin 27.

A window 33 is provided whereby access may be had to the chamber 29 for lubrication or the like, and for the manipulation of the cotter pin 31.

The operation of the device is as follows:

In topographic field work, with a given line, the device is positioned over this line, and the prongs 12 are forced into the ground at or through the line. The rod 5 is, of course, adjusted to the selected elevation. The holding element 26 is now parallel with this line. By turning the upper plate or disk 24, the same being free to rise in opposition to the spring 30, the lugs 25 will leave the first set of recesses 25 and enter the next set, whereby the upper plate 24 is again held in the adjusted position at 90° from the original position. In a similar manner the upper plate may be moved to the remaining adjusted positions, at 90°, throughout the remaining 360°. While it is preferred to provide the adjustment for holding or locking of the upper plate, at the 90° positions, the invention is not necessarily restricted to this precise arrangement, as other angular arrangements of the recesses and lugs may be had.

As stated, the long prong 21 and clamp are only used when the device is employed for ranging purposes.

It is to be understood that the form of my invention herewith shown and described is to be taken as a preferred example of the invention, and that various changes in the shape, size, and arrangement of parts, may be resorted to, without departing from the spirit of my invention, or the scope of the subjoined claims.

Having fully described my invention, what I claim as new is:

1. In a geometrical instrument, a rod adapted to be substantially vertically arranged in use and provided at its lower end with a ground engaging part and having a longitudinal bore extending through its upper end and a window leading into the bore, a substantially horizontal plate secured to the upper end of the rod and having an opening in communication with the bore and also having spaced recesses, an upper substantially horizontal plate mounted upon the first named plate for rotation with relation thereto and having a projection to enter the recesses, a pin secured to the upper disk and projecting below the same and adapted to be passed downwardly through the opening in the first named plate and extending into the bore for a substantial distance, a stop element detachably connected with the pin and removable through the window, a spring mounted upon the pin within the bore and engaging the first named plate and the stop element to draw the plates together, and a holding device mounted upon the upper plate.

2. A rod to be vertically arranged in use, a sleeve mounted upon the rod, a plate carried by the sleeve, a second plate arranged upon the first plate, said plates having releasable holding parts, a pin secured to the second plate and extending through the first plate to pivotally connect them, a spring mounted around the pin between an abutment upon the pin and the first mentioned plate and serving to draw the plates together, said sleeve serving to house the pin and spring and also serving to attach the first named plate to the rod, and means mounted upon the second named plate for holding an instrument.

3. In a geometrical instrument, a rod adapted to be substantially vertically disposed in use, a flat relatively wide plate attached to the lower end of the rod and disposed at substantially a right angle thereto, said plate being provided substantially centrally thereof with an opening, a pair of depending prongs arranged beneath the plate and attached thereto and disposed upon opposite sides of said opening, said prongs and opening being in alignment, an adjustable two-part clamp mounted upon the upper side of the plate, and a prong attached to one part of the clamp and extending downwardly through the opening of the plate, the last named prong being longer than the first named prongs, a hand level holding device and adjustable means connecting the device with the upper end of the rod so that such device may be turned in a substantially horizontal plane about substantially the longitudinal axis of the rod.

4. In a geometrical instrument, a rod adapted to be substantially vertically arranged in use, a relatively wide plate arranged near and beneath the rod, a pair of spaced straps arranged above the plate and attached thereto and having longitudinal slots, said straps being arranged upon opposite sides of the rod, clamping means carried by the rod and extending through the slots and so constructed that the rod may be raised and lowered with relation to the plate and clamp to the straps in a selected adjusted elevation, depending spaced prongs carried by the plate and adapted to be inserted in the ground at a given line, a horizontal plate pivotally mounted upon the upper end of the rod to be turned at substantially a horizontal plane, means to hold the plate at a selected adjusted horizontal position, and a holding element carried by the plate.

5. A rod to be substantially vertically arranged in use, a sleeve carried by the upper end of the rod and having a window formed in its side, a lower plate attached to the sleeve and having an opening, an upper plate mounted upon the lower plate, said plates having releasable holding means, a pin secured to the upper plate and extending through the opening in the lower plate and serving to pivotally connect the plates, a stop element detachably connected with the pin and removable through the window, a spring mounted upon the pin and engaging the lower plate and the stop element to draw the plates together, the sleeve serving to house the pin and spring and to connect the lower plate with the rod, and a holding device mounted upon the upper plate.

OTTO F. BUZHARDT.
